attorney

UNITED STATES PATENT OFFICE.

CHARLES H. ALLEN, OF ATTLEBORO, MASSACHUSETTS.

COLLAR-HOLDER.

1,387,878.

Specification of Letters Patent. Patented Aug. 16, 1921.

Application filed June 6, 1921. Serial No. 475,297.

To all whom it may concern:

Be it known that I, CHARLES H. ALLEN, a citizen of the United States, residing at Attleboro, in the county of Bristol and State 5 of Massachusetts, have invented certain new and useful Improvements in Collar-Holders, of which the following is a specification.

My invention relates to soft collar holders of the double clamp type and has for its essential objects inexpensiveness of manufacture, facility of application, security of engagement without injury to the fabric, and interlocking security of the clamping parts against transverse movement of the rear 10 arm members relatively to the loop portions carrying the arm members.

To the above ends my invention consists in such parts and in such combinations of parts as fall within the scope of the appended 15 claims.

In the accompanying drawings which form a part of this specification,

Figures 1 and 2 are front and side elevations respectively of the blank from which 20 the holder is formed,

Figs. 3 and 4, front and plan views respectively of the collar holder, and

Fig. 5, a section on line 5—5 of Fig. 3.

Like reference characters indicate like 25 parts throughout the views.

In detail my holder is initially cut by suitable tools from resilient thin sheet metal into an oblong body having near each end an arch 8 cut from the material and raised 30 from the plane of the material, and having similar arches 9 cut and raised from the plane of the material at each side of the center of the body.

The blank is next bent up into final form 35 which consists of an oblong, preferably slightly curved body 10 provided at each end with a rearward and inward bend forming an open loop 11, whence the material extends inwardly and, in this instance, slightly forwardly, forming a forward arm 12, whose inner portion is bent downwardly and out-

wardly forming a reversely disposed open loop 13 from which the material extends outwardly, and in this instance, slightly rearwardly, forming a free rear arm 14 projecting slightly beyond the end of the first loop. By the bending operation the arches 9 with the oblong opening formed by their elevation from the plane of the material, occur in intermediate portions of the arms 12 and 50 are forwardly directed. In intermediate portions of the arms 14 occurs the arches 8 raised from the plane of the material in front of the resultant oblong openings 16. 55

It will be noted that the arches 8 extend 60 forwardly into the openings 15 so that the lateral walls which bound the openings are on each side of the apices of the arches 8 and thus tend to lock the latter against any lateral movement, and thus prevent any upward or downward movement of the arms 14. 65

In use the collar corners are inserted between the arms 14 and 12.

I claim:

1. In a collar holder, an oblong body, inwardly directed arms upon the ends of the body, outwardly directed arms upon the inner ends of the first arms, arches cut from intermediate portions of the first arms and raised from the planes thereof, and similar 70 arches cut from intermediate portions of the second arms and raised from the planes thereof in the direction of the first arches. 75

2. In a collar holder, an oblong body, inwardly directed arms on the ends of the body behind the same, outwardly directed arms upon the inner ends of the first arms in the rear of the latter, forwardly directed arches cut from intermediate portions of the forward arms forming slots in said 80 arms, similar arches cut from intermediate portions of the rear arms and raised from the planes thereof and adapted to register in the slots. 85

In testimony whereof I have affixed my 90 signature.

CHARLES H. ALLEN.
